AIR DIVERTER ATTACHMENT

Caryl Beimuller, Skokie, Ill.

Application March 3, 1942, Serial No. 433,169

7 Claims. (CL 230—274)

The present invention relates to an air diverter attachment adapted to be used in connection with a grille through which air currents emanate, either by convection or are forcibly projected by a fan or the like. The function of devices of this character is to distribute and circulate the air currents emanating through the grille for distribution over a relatively wide, angular range.

The attachment constituting the present invention is especially suitable for use in conjunction with non-oscillating types of electric fans. It is to be understood, however, that the device is also capable of use in connection with grilles of various other types of apparatus through which air currents emanate, either by convection or by being forcibly projected by use of a fan, such as in connection with the radiator of a unit heater, or in connection with grilles used in conjunction with various types of apparatus for either heating or cooling purposes.

The air diverter attachment herein illustrated lends itself for convenient adaptation to the major range of sizes of electric fans of the stationary or non-oscillating types. It has been recognized that in rooms containing a large number of persons, a stationary or non-oscillating fan is often found to be objectionable and unsatisfactory in that too much air is concentrated for movement in a limited path, while the air in adjacent areas of the room remains substantially inert. The air diverter attachment embodying the present invention, when associated with a stationary or non-oscillating fan, functions to gradually and continuously shift and direct the air currents over a substantial angular range, thereby causing agitation and circulation of the air throughout a greater area of the room. The use of my novel air diverter attachment in conjunction with relatively large types of non-oscillating fans results in obtaining the above mentioned advantages, which could not otherwise be obtained.

It is known that the larger types of non-oscillating fans, such as the pedestal type of fan or the platform mounted fan, which usually range in sizes of eighteen-inch diameter and larger, are relatively heavy in construction and weight, and the primary reason why such large size fans are not made in the oscillating form is due to two factors: One, because of the relatively large size and weight, and secondly, because of the great increase in cost which would result largely from the type of supporting structure and actuating means required in order to take care of the substantial increase in weight which must be

properly supported during the time that the fan proper is oscillated. In the larger types of fans a relatively large size of motor is utilized, thus adding considerably to the amount of weight which must be properly supported during oscillation of the entire fan.

One of the objects of the present invention is to provide a novel form of attachment of the character indicated, characterized by the provision of a pair of parallel, spaced apart panels or vanes disposed in front of the grille through which air currents emanate, and wherein said panels are oscillated for effecting continuous, uniform distribution of the currents throughout a relatively wide angular range.

Another object is to provide a novel self-contained, unitary air diverter attachment constructed and arranged so as to permit quick and easy detachable securement to a grille through which air currents emanate, and characterized by the provision of a pair of vertically disposed, parallel, spaced apart panels or vanes operated by power driven mechanism for movement in unison and in substantially parallel relation to each other, for distributing the air currents throughout a relatively wide angular range.

A further object is to provide a novel air diverter attachment of the character indicated, including a housing adapted for detachable securement to a grille through which the air currents emanate, and wherein the housing is provided at opposite sides with a pair of vertically spaced apart arms, to the outer ends of each pair of which is pivotally connected a vertically disposed panel or vane, together with electrically energized power driven mechanism within the housing and having operating connections to the panels for oscillating them to and fro, about their pivotal connections.

A still further object is to provide a novel and improved air diverter attachment of the character indicated, wherein the parts are of relatively simplified construction and arrangement for enabling quick and easy assembly, and which permits of economical manufacture.

Other objects and advantages of this invention will be apparent from the following description, taken in connection with the accompanying drawings, in which:

Figure 1 is a front elevational view of the air diverter attachment, embodying the present invention.

Figure 2 is a vertical sectional view through the attachment, taken substantially as indicated

at line 2—2 on Figure 1, showing the attachment in association with a power driven fan;

Figure 3 is a side elevational view of the outer surface of one of the air diverter panels, showing its mode of support and taken substantially as indicated at line 3—3 of Figure 1;

Figure 4 is a fragmentary top plan view of one of the air diverter panels, showing its mode of support;

Figure 5 is a fragmentary section through a portion of the panel and one of its supporting arms, taken substantially as indicated at line 5—5 on Figure 4;

Figure 6 is a top plan view of the air diverter attachment shown mounted on a fan guard or grille;

Figure 7 is an enlarged vertical sectional view through the housing and mounting, taken substantially as indicated at line 7—7 on Figure 6;

Figure 8 is an enlarged fragmentary vertical sectional view taken at line 8—8 on Figure 7, showing details of construction and operating connections for oscillating the panels;

Figure 9 is a transverse detail, sectional view through the mounting of the device as applied to a fan guard, taken substantially as indicated at line 9—9 on Figure 7.

For the purposes of illustration, I have herein shown my novel air diverter attachment as used in connection with a non-oscillating type of power driven fan, which is herein shown fragmentarily, and includes a fan blade, indicated at 10, which is enclosed and protected by a guard or grille of conventional design, as indicated at 11. Such guards or grilles, as is well known, are of conventional form and are usually fabricated of wire or flat bar stock elements.

The air diverter attachment proper includes a frame structure composed of a hollow housing 15, which is open at its rear end, as clearly seen in Figure 7 of the drawings. Said housing may be formed of any suitable material, such as metal or plastic. As shown in the drawings, said housing is formed at top and bottom with parallel, flat mounting surfaces, as indicated at 17, the rear edges of which terminate in transversely extending, undercut slots 18. Said frame structure also includes two pairs of oppositely disposed supporting arms 20 arranged on opposite sides of the housing 15. Said arms each include a flat base portion 21, adapted to be seated on the respective flat mounting surfaces 17 of the housing, with the rearward marginal portion of said base portion 21 seated in the undercut grooves 18, as clearly seen in the drawings, so that each of said arms may be conveniently and rigidly secured in position on the housing by a single fastening screw, as indicated at 23. The arms of the respective pairs diverge with respect to each other and terminate at their outer ends in horizontally extending terminal portions 26 of generally circular outline, as may be clearly seen in Figure 4 of the drawings.

Pivotal mounted on the terminal portions 26 of each pair of arms is a vertically disposed, elongated panel or vane 28, formed with a pair of oppositely arranged T-shaped slots 29, with the horizontal portions of said slots registering with and accommodating the terminal mounting portions 26 of the respective arms. Each of said panels is detachably secured to the respective pairs of arms by a novel arrangement consisting of a locking rod 30, formed with laterally offset terminal portions 31 and 32, respectively, adapted to be projected through apertures 26a formed

slightly outwardly off center with respect to the generally circular terminal portions 26 of said arms. The purpose of this offset relationship is to provide substantially central support of the panel 28 on the respective terminal portions 26 of said arms, as may be seen in Figures 4 and 5 of the drawings. The vertical portions of the T-shaped slots 29 in the panel permit insertion of the offset portions 31 and 32 of said rod 30, incident to connection of the terminal portions 26 of said arms in proper relationship to the panel 28.

After the panel is placed upon the supporting terminals 26 of the arms, the terminal end 31 of the rod 30 is first fed through the vertical portion of the upper slot 29 in a manner so as to project the offset portions 31 through the aperture 26a of the terminal portion 26 of said upper arm and disposing the offset portion 31 on the exterior of the panel, as seen in Figure 1 of the drawings. Said rod is then pushed upwardly until the shoulder portion of the rod, which serves to connect the offset portion 31 with the main body portion of the rod, encounters the under side of the terminal portion 26 of the upper arm. Then the offset portion 32 at the lower end of the rod is projected through the vertical portion of the lower slot 29 so as to dispose the end thereof through the slot at the opposite side of the panel into the opening 26a in the terminal portion 26 of the lower arm. The rod 30 is then pushed downwardly to the position as seen in Figure 1 of the drawings, and thus serves to lock the panel permanently in pivotal relation on the supporting terminals 26 of the respective pairs of arms 20.

The arms 20 are formed as sheet metal stampings and, in order to obtain lightness of weight and still attain adequate rigidity for properly supporting the panels or vanes 28, the angular intermediate portions of said arms is formed with a central rib 20a.

Mounted within the housing 15, as clearly seen in Figures 7 and 8 of the drawings, is an electric motor 35 such as a clock type, synchronous motor, the housing of which terminates at its forward end in a housing 36 which it may be understood serves to enclose suitable speed-reducing gearing, so that the operating drive shaft indicated at 37 projecting from the housing portion 36 rotates at relatively low speed, such as two or three R. P. M. Said housing 36 is provided with a pair of outwardly projecting lugs or ears 38 which serve as mounting lugs for securing the motor and reduction gearing as a unit, by means of screws 39, to the bosses 40 formed in the interior of the housing 15.

Mounted on the drive shaft 37 is a crank arm 42 of generally U-shaped formation, with the outer leg as indicated at 42a, of greater length than the other leg. Said crank arm is rigidly secured to the outer end of the drive shaft 37 by means of a set screw 43. Pivotal and swivelly connected to the outer end of the leg 42a of the crank arm is a pair of oppositely extending connecting rods 45 which extend through vertically disposed, elongated slots 46 formed in the opposite sides of the nose portion of the housing 15, as seen in the drawings. The outer ends of these rods are formed with down-turned terminal portions 47, adapted to be projected through apertures formed in horizontally disposed angle clips 48 which are formed as an integral part of an eyelet type of rivet, indicated at 49, mounted in the panel substantially at its longitudinal and transverse centers. The terminal

portions 47 of the connecting rods are formed with slight enlargements, as indicated at 47a, so as to require slight pressure in projecting through the aperture in the clip members 48 so as to releasably lock the connecting rods in position.

It will now be apparent that as the drive shaft 37 rotates, rotary motion is imparted to the crank arm 42, to cause the connecting rods 45 to move first in one lateral direction and then in the opposite direction, and thus results in moving both panels 28 as a unit in an oscillating manner throughout a substantial angular range, as indicated in dotted outline in Figure 6. It will be apparent that by providing a pivotal mounting for the respective panels or vanes, located a substantial distance inwardly from the rear edge of the panels, it is possible to utilize and act upon a greater angular range of the air currents passing through the grille 11 than would be possible if the pivotal axis were located adjacent the rear edge of the panel.

In order to adapt the unitary air diverter attachment for use in connection with various sizes of fans and of various grille formations, I have provided a special mounting fixture which consists in an elongated plate 50 which is formed with a pair of inturned lugs 51 for securing to the interior of the open end of the housing 18 by means of screws 52, as seen in Figure 7 of the drawings. The outer ends of the elongated plate 50 are formed with apertures for accommodating bolts 54 for cooperative engagement with a clamping member which is composed of an annular ring 55, to the back surface of which is rigidly secured, such as by welding, substantially centrally thereof, a pair of closely spaced apart bars 56, as seen in the drawings. Thus, when it is desired to secure the attachment to a grille, such as indicated at 11, the clamping member composed of the ring 55 and the bars 56 is inserted on the inner side of the grille and the bolts 54 are then projected through the apertures in the outer ends of the plate 50 and between the bars 56, so as to rigidly clamp the grille 11 between the plate 50 and the annular ring 55, as seen in the drawings.

While I have herein shown and described a preferred embodiment of my invention, manifestly it is capable of modification and rearrangement of parts without departing from the spirit and scope thereof. I do not, therefore, wish to be understood as limiting this invention to the precise form as herein disclosed, except as I may be so limited by the appended claims.

What I claim as my invention and desire to protect by Letters Patent of the United States is:

1. An air diverter attachment adapted to be connected to a grille through which air currents emanate, comprising a housing, two pairs of oppositely extending supporting arms connected to and extending from opposite sides of said housing, the arms of each pair being vertically spaced apart and having their outer ends disposed in substantially vertical alignment, a pair of upright parallel panels pivotally mounted respectively on the outer ends of said pairs of arms, electrically operated power driven mechanism within said housing, and means connecting said mechanism to said panels for oscillating them about their pivot axes.

2. An air diverter attachment adapted to be connected to a grille through which air currents emanate, comprising a housing, two pairs of oppositely extending supporting arms connected to

and extending from opposite sides of said housing, the arms of each pair being vertically spaced apart and having their outer ends disposed in substantially vertical alignment, a pair of upright parallel panels pivotally mounted respectively on the outer ends of said pairs of arms a substantial distance forwardly of the rear edge of said panels, electrically operated power driven mechanism within said housing, and means connecting said mechanism to said panels for oscillating them about their pivot axes.

3. An air diverter attachment adapted to be connected to a grille through which air currents emanate, comprising a housing, two pairs of oppositely extending supporting arms connected to and extending from opposite sides of said housing, the arms of each pair being vertically spaced apart and having their outer ends disposed in substantially vertical alignment, a pair of upright parallel panels pivotally mounted respectively on the outer ends of said pairs of arms, the outer ends of said arms being formed as flat horizontally disposed terminal portions adapted to be projected through horizontal slots in said panels to provide a substantial bearing surface for the latter, electrically operated power driven mechanism within said housing, and means connecting said mechanism to said panels for oscillating them about their pivot axes.

4. An air diverter attachment adapted to be connected to a grille through which air currents emanate, comprising a housing, two pairs of oppositely extending supporting arms connected to and extending from opposite sides of said housing, the arms of each pair being vertically spaced apart and having their outer ends disposed in substantially vertical alignment, a pair of upright parallel panels pivotally mounted respectively on the outer ends of said pairs of arms, the outer ends of said arms being formed as flat horizontally disposed terminal portions adapted to be projected through horizontal slots in said panels to provide a substantial bearing surface for the latter, a single upright rod for connecting each panel to a pair of arms and having the opposite ends thereof formed with laterally offset portions adapted to be projected through vertical slots, contiguous with the horizontal slots in said panels, so as to permit insertion through apertures in said terminal portions of the arms to provide said pivotal connections of the panels to said arms, electrically operated power driven mechanism within said housing, and means connecting said mechanism to said panels for oscillating them about their pivot axes.

5. An air diverter attachment adapted to be connected to a grille through which air currents emanate, comprising a housing, two pairs of oppositely extending supporting arms connected to and extending from opposite sides of said housing, the arms of each pair being vertically spaced apart and having their outer ends disposed in substantially vertical alignment, a pair of upright parallel panels pivotally mounted respectively on the outer ends of said pairs of arms, electrically operated power driven mechanism within said housing and including a rotary crank arm, and a pair of oppositely extending connecting rods each being connected at one end to said crank arm and extending through slots in said housing and having their opposite ends pivotally connected to the respective panels.

6. An air diverter attachment adapted to be connected to a grille through which air currents

emanate, comprising a housing, clamping means for detachably securing the rear end of said housing firmly to said grille, two pairs of oppositely extending supporting arms connected to and extending from opposite sides of said housing, the arms of each pair being vertically spaced apart and having their outer ends disposed in substantially vertical alignment, a pair of upright parallel panels pivotally mounted respectively on the outer ends of said pairs of arms, electrically operated power driven mechanism within said housing, and means connecting said mechanism to said panels for oscillating them about their pivot axes.

7. An air diverter attachment adapted to be 15

connected to a grille through which air currents emanate, comprising a housing, two pairs of oppositely extending supporting arms connected to and extending from opposite sides of said housing, the arms of each pair being vertically spaced apart and having their outer ends disposed in substantially vertical alignment, a pair of upright parallel panels pivotally mounted respectively on the outer ends of said pair of arms, electrically operated power driven mechanism within said housing, and means connecting said mechanism to said panels for oscillating them in union and in substantially parallel relation to each other at all times.

CARYL REIMULLER.
